3,340,630 9/1967 Becker ..... 40/21 C

[76] Inventor: Esther O. Mayfield, 5565 Thunderbird La., La Jolla, Calif. 92037

Primary Examiner—James R. Largen

[] Term: 14 Years

[57]

CLAIM

[21] Appl. No.: 832,840

The ornamental design for an identification tag for an animal collar or similar article, as shown and described.

[22] Filed: Sep. 12, 1977

DESCRIPTION

[51] Int. Cl. ..... D30—04
[52] U.S. Cl. D30/38
[58] Field of Search ..... 119/106; 40/21 C, 303, 40/304, 21 R, 21 C, 10 D

FIG. 1 is a perspective view of an identification tag for an animal collar or similar article showing my new design;

FIG. 2 is a top plan view thereof;

FIG. 3 is a side elevational view thereof;

FIG. 4 is a cross sectional view taken on line 4—4 of FIG. 2; and

FIG. 5 is a cross sectional view taken on line 5—5 of FIG. 2.

The fragmentary broken line representation of an animal collar in FIGS. 1 and 2 is for purposes of illustration only.
